DESIGN FOR A SPRING TESTER OR SIMILAR ARTICLE

Paul A. Sturtevant, Addison, Ill.

Application March 14, 1941, Serial No. 99,594

Term of patent 14 years

To all whom it may concern:

Be it known that I, Paul A. Sturtevant, a citizen of the United States, residing at Addison, in the county of Du Page, and State of Illinois, have invented a new, original, and ornamental Design for a Spring Tester or Similar Article, of which the following is a specification, reference being had to the accompanying drawing, forming a part thereof.

Figure 1 is a perspective view of a spring tester or similar article showing my new design; Fig. 2 is an enlarged plan view of Fig. 1; and Fig. 3 is a front elevational view of Fig. 2.

I claim:

The ornamental design for a spring tester or similar article, substantially as shown.

PAUL A. STURTEVANT.
